UNITED STATES PATENT OFFICE.

WILLIAM HOLT, OF CHICAGO, ILLINOIS.

MOISTENER FOR ENVELOPS, &c.

SPECIFICATION forming part of Letters Patent No. 775,299, dated November 22, 1904.

Application filed August 1, 1904. Serial No. 219,003. (No model.)

To all whom it may concern:

Be it known that I, WILLIAM HOLT, a citizen of the United States, residing in Chicago, in the county of Cook and State of Illinois, 5 have invented a new and useful Improvement in Moisteners for Envelops, &c., of which the following is a specification.

This invention is intended to supply an improved device adapted to be kept upon the 10 desk and to be used in moistening envelops and stamps preparatory to sealing and mailing them.

It embodies a vessel for holding the water, a piece of felt in said vessel supported at its 15 center and having its ends extending down into the water, so that the center remains saturated at all times, and a perforated cover of thin metal which is in contact with the supported portion of the felt, so that by moving 20 the surface to be moistened over the cover enough moisture will be taken up by it to enable the sealing or stamping of the envelop.

The nature of the construction is fully disclosed in the accompanying drawings, in 25 which—

Figure 1 is a plan of my improved moistener. Fig. 2 is a section of the same on line 2 2 of Fig. 1. Fig. 3 shows the felt detached and extended, and Fig. 4 is a plan of the 30 device for supporting the felt. Figs. 3 and 4 are upon a reduced scale.

In the drawings, 5 represents the water-holding vessel. It is preferably made in circular form from sheet metal and may be 35 stamped therefrom, and by preference it is beaded all around, as at 6. Within the vessel I place a strip of felt or other suitable material adapted to lift the necessary amount of moisture from the body of water in the vessel 40 5 and be ready at all times to supply it to the envelops or stamps. I prefer to cut the felt as shown in Fig. 3—that is, with a central circular body 7, conforming in size to the perforated portion of the cover hereinafter described and with wings 8 adapted to dip

into the water, and thus keep the center 7 supplied therewith. The felt or other moistening material is supported at its center by a U-shaped metal frame or stand 9, the limbs whereof rest upon the floor of the water vessel and have sufficient height to keep the center 7 out of the water and up against the perforations in the cover. 50

The cover has a flange 10 setting down over and fitting the top edge of the water vessel. 55 The center 11 of the cover is raised and perforated and conforms to the center of the felt, with which it is in close contact, and between the raised center and the flange 11 a depressed annulus 12 is formed in the cover adapted to 60 catch any excess water which may collect on top of the device. In this annulus is located the opening 13, through which the water vessel is charged, and such opening gives drainage to excess water collecting in the annulus. 65 The cover is preferably held in place by friction between its flange and the wall of the water vessel; but it may be otherwise secured, if preferred.

The perforated cover is made of thin material, so that the moisture readily finds its way to the top surface, and, if desired, may be made thin so as to permit it to yield to slight pressure, and thus increase the moisture supply by compressing the felt. 70

The device can also be used by bank-tellers for moistening the fingers preparatory to counting currency. 75

I claim—

1. The moistener, consisting of a water vessel, a perforated cover for said vessel, a piece of felt adapted to supply moisture to the perforated cover, and a U-shaped frame supporting the body of the felt above the water, the felt having depending portions dipping into 80 the water. 85

2. The moistener, consisting of a water vessel, a perforated cover for said vessel having a depressed annulus adapted to catch excess water escaping through the perforations, a 90

piece of felt adapted to supply moisture to the perforations of the cover, and means for supporting the felt.

3. The moistener, consisting of a water vessel, a perforated cover for said vessel having a depressed annulus, a felt piece arranged under the cover for lifting the water to the per-

forations in the same and a U-shaped frame supporting the felt, the felt having portions dipping permanently in the water.

WILLIAM HOLT.
